UNITED STATES PATENT OFFICE

164,309

ELECTRICALLY OPERATED AMUSEMENT
MACHINE

Bernard T. McManus, Lander, Wyo., assignor to
P & M Enterprises, Rock Springs, Wyo., a corporation of Wyoming

Application October 4, 1950, Serial No. 12,444

Term of patent 14 years

(Cl. D34—5)

To all whom it may concern:

Be it known that I, Bernard T. McManus, a citizen of the United States, residing at Lander, county of Fremont and State of Wyoming, have invented a new and original and ornamental Design for an Electrically Operated Amusement Machine, of which the following is a specification, reference being had to the accompanying drawings, forming a part thereof, in which:

Fig. 1 is a front elevational view of an electrically operated amusement machine which shows my new design;

Fig. 2 is a top plan view thereof;

Fig. 3 is a side elevational view thereof; and

Fig. 4 is an elevational view of the other side of my electrically operated amusement machine.

The dominant features of my design reside in the portions shown in full lines.

I claim:

The ornamental design for an electrically operated amusement machine, as shown and described.

BERNARD T. McMANUS.
